AIR COMPRESSOR

William U. Griffiths, Philadelphia, Pa.

Application September 18, 1933, Serial No. 689,839

7 Claims. (Cl. 230—91)

This invention relates to apparatus for compressing air and involves an improvement in apparatus wherein air or other gaseous fluids are transferred from one location to another by the successive admission of water or other liquid into a container and its discharge therefrom, the transferred air preferably being stored in a compression tank for use in pumping beer and other liquids in the operation of dispensing the same.

10 In the type of apparatus to which the improvement relates a continuous flow of water is admitted into a container and a water outlet of greater capacity than the water inlet is provided with a float actuated discharge valve arranged to be opened by the float when the water reaches the desired level in the container, and the air pressure therein is relieved. The container is provided with a valve controlled air intake and a valve controlled air outlet through which air 15 is expelled as the container fills with water. In such apparatus the air intake is ordinarily provided with a float actuated valve, the float being so arranged as to open the valve when the water reaches the desired height in the container. In 20 order that the valve controlling the air intake may not close during the period of water discharge from the container, it is essential that some means be provided for holding the air intake valve in its open position during the time 25 that the water discharge valve is open.

One of the principal objects of the present invention is the provision of improved means for simultaneously holding the water discharge valve and the air intake valve in open positions. A 30 further object of the invention is the provision of improved float actuated means for retaining the water discharge valve in open position. A still further object of the invention is the provision of improved float actuated means for holding the air intake valve in open position during 35 the period of water discharge from the container.

Still further objects and advantages of the improvement will be apparent from the following description, taken with the accompanying drawings, wherein:

Fig. 1 is a vertical sectional view of air pumping and compressing apparatus embodying one form of my improvement and showing the position of the various parts during that portion of the cycle of operation when air is being ejected from the apparatus into a storage or compression tank;

Fig. 2 is a plan view of the water discharge valve;

Fig. 3 is a detailed sectional view showing the water discharge valve in open position;

Fig. 4 is a vertical sectional view similar to Fig. 1 but showing a modified form of water discharge valve and float operated means for retaining the water discharge valve and the air intake valve in open positions;

Fig. 5 is a detailed sectional view showing the closed position of the modified form of water discharge valve illustrated in Fig. 4; and

Fig. 6 is a plan view of the water discharge valve shown in Figs. 4 and 5.

As I have illustrated the same herein, my improvement is embodied in a container 10 having a water inlet 11 preferably located in the bottom portion thereof and so arranged as to provide a continuous flow of water under pressure. The bottom of the container is provided with a suitable nipple 12 forming a water outlet having a greater capacity than the water inlet in order that water may be discharged when the outlet is open notwithstanding the continuous flow of water into the container. The water outlet 12 is provided with a discharge valve 13 having an elongated valve stem or actuating rod 14 extending therebelow through a guide 15 supported by spider arms 16 extending inwardly from the water outlet 12. The valve stem 14 extends vertically within the container 10 and has its upper end freely slidable in a guide member 17 projecting inwardly from the container wall. A main float 18 for opening the water discharge valve 13 is slidably mounted upon the valve actuating rod 14 between two spaced stop members, such as cotter pins 19.

An air outlet 20 in the upper end of the container is controlled by a combined float and check valve 21 which cooperates with the valve seat 22 to prevent the backward flow of air from the air storage tank through the air outlet pipe 23, and with the valve seat 24 to prevent the passage of water into the storage tank in case of any failure of the parts of the device to function properly.

The upper portion of the container 10 is also provided with an air intake 25 extending through the side wall thereof and connected to any suitable source of clean, fresh air. The inner end of the air intake 25 is bent upwardly and is controlled by a pressure relief and air intake valve 26 secured to a valve actuating lever 27, one end of which is pivoted to a bracket 28 extending outwardly from the air intake pipe, and the opposite end of which carries a float 29 which serves to open the air intake valve when the water reaches the necessary height in the container. As

shown herein, the upper end of the valve actuating rod 14 is provided with a transversely extending plate 30 which forms a seat for the float 29 so that when the water discharge valve 13 and its actuating rod 14 are in their uppermost positions the float 29 will be held in its raised position notwithstanding the lowering of the water level in the container, and consequently the air intake valve 26 will be held in open position when the actuated rod 14 is in elevated position. To insure the closing of the air intake valve when the actuating rod 14 moves downwardly, it is preferable that the plate 30 be out of contact with the float 29 when the actuating rod is in its lowermost position, as shown in Fig. 1.

In order to retain the water discharge valve 13 in open position and also retain the air intake valve 26 in open position during the period of discharge of water from the container, a latch 31 is pivoted at its lower end upon a bracket 32 extending outwardly from the water outlet 12, and this latch is provided intermediate its length with a shoulder 33 for engagement beneath an extended portion 34 on the edge of the water discharge valve between two oppositely arranged guide members 35, as shown in Fig. 3. The extreme upper end of the latch 31 is provided with a transversely bent portion 36 which serves to prevent undue movement of the water discharge valve in an upward direction. Secured to the latch 31 is a float 37 which tends to force the latch inwardly toward the water discharge valve whereby the inclined portion 38 thereof tends to hold the discharge valve closed during that portion of the cycle of operation of the device when air is being expelled therefrom into the storage tank. As the level of the water lowers to the bottom of the container during the period of water discharge the latch float 37 is permitted to drop, thereby disengaging the shoulder 33 of the latch from beneath the water discharge valve and permitting this valve to move into its closed position.

As will be clear from Fig. 1 of the drawings, when the water discharge valve is in its open position and is retained therein by the float actuated latch 31, the elongated valve stem 14 is likewise held in its raised position with the plate 30 thereon in engagement with the upper float 29 to thereby hold the air intake valve 26 in open position. The latch float therefore serves the purpose of retaining both the water discharge valve 13 and the air intake valve 26 in their open positions during that portion of the cycle of operation of the apparatus when water is being discharged therefrom.

In the modified form of apparatus shown in Figs. 4, 5, and 6, the water discharge valve 39 is pivotally mounted intermediate the ends of a lever 40 one end of which is pivoted to a bracket 41 extending outwardly from the water outlet 12. The opposite end of the lever 40 has pivoted thereto the lower end of an elongated valve actuating rod 42 upon which the main float 18' is slidably mounted.

In this modification of the device the latch 43 for retaining the water discharge valve 39 in open position is provided with an inclined edge 44 against which the free end of the valve operating lever 40 contacts, and this inclined edge tends to retain the water discharge valve in closed position under the influence of the float 37' to which the latch is secured. As the discharge valve 39 is raised by the main float 18' the upper end of the latch 43 engages beneath the free end of the lever 40, as shown in Fig. 4, and thereby retains the

valve in open position until the level of the water in the container lowers sufficiently to permit the float 37' to drop.

The manner in which the float actuated latch 43 illustrated in Figs. 4, 5 and 6 operates to retain the air intake valve 26 in open position does not differ essentially from the operation of the float actuated latch 31 disclosed in Figs. 1, 2 and 3 and heretofore described, and further description thereof is therefore omitted.

In Fig. 1 of the drawings I have shown the relative positions of the various parts of the device during that portion of the cycle of operation when air is being expelled to a storage tank through the air outlet pipe 23 and the level of the water in the container 10 has risen sufficiently to lift the float 18 to the limit of its movement on the valve actuating stem 14 but has not risen sufficiently to lift the float 29 and thereby open the air intake valve 26. When the level of the water in the container rises sufficiently to lift the float 29 and thereby open the valve 26, the air pressure in the container is immediately relieved by the escape of air through the air intake 25. With this decrease of the air pressure within the container, the buoyancy of float 18 is sufficient to lift the water discharge valve 13 against the pressure thereon and the pressure exerted by the inclined edge of the float operated latch. The discharge valve 13 is retained in open position by means of the float operated latch, and this latch also serves to retain the valve 26 in open position during the period of water discharge by reason of the engagement of the plate 30 on the upper end of the valve stem 14 with the float 29. The valves 13 and 26 are consequently held in their open positions until the level of the water in the container falls sufficiently to permit the float 37 to drop and thereby disengage the latch from the water discharge valve. At this point the water discharge valve moves to its closed position, carrying with it the valve stem 14 and the plate 30, whereupon the float 29 is permitted to drop and thereby close the valve 26.

Inasmuch as water is flowing into the container continuously through the water inlet 11 the level of the water in the container begins to rise as soon as the water discharge valve moves into its closed position, and the water level continues to rise until it reaches such a height as is necessary to operate the float 29, whereupon the cycle of operation continues as above described. Fig. 4 of the drawings shows the relative positions of the water discharge valve and the air inlet valve during the period of water discharge, and it will be noted that the float operated latch not only serves to retain the water discharge valve in open position but also operates, through the valve actuating rod and the float 29, to retain the valve 26 in open position, both valves being retained in open position until the water level lowers in the container sufficiently to permit the float actuated latch to be disengaged from the water discharge valve.

While I have disclosed herein two forms of water discharge valve and cooperating latching means, it will be understood that other changes may be made in the device without departing from my invention so long as these changes come within the scope of the appended claims.

What I desire to claim by Letters Patent is:

1. An air compressor comprising a container having a water inlet, a water outlet in the bottom thereof, and an air inlet and an air outlet in the top thereof, a check valve in said air outlet, a dis-

charge valve for said water outlet, a float connected to said discharge valve for opening the same, an air inlet valve, a float for opening said air inlet valve, means controlled by the movement of said discharge valve for holding said air inlet valve open when said discharge valve is in open position, and a float mounted in the bottom of said container for resisting opening movement of said discharge valve and holding the same in open position.

2. An air compressor comprising a container having a water inlet, a water outlet in the bottom thereof, and an air inlet and an air outlet in the top thereof, a check valve in said air outlet, a discharge valve for said water outlet, a valve stem secured to said discharge valve and extending upwardly therefrom, a float mounted for limited longitudinal movement on said valve stem for opening said discharge valve, an air inlet valve, a float in the path of movement of said valve stem and connected to said air inlet valve for opening the same, float actuated means for resisting the opening of said discharge valve, and float actuated means for holding said discharge valve in open position.

3. An air compressor comprising a container having a water inlet, a water outlet in the bottom thereof, and an air inlet and an air outlet in the top thereof, a check valve in said air outlet, a discharge valve for said water outlet, a valve stem secured to said discharge valve and extending upwardly therefrom, a pair of spaced stops on said valve stem, a float mounted for longitudinal movement on said valve stem between said stops for opening said discharge valve, an air inlet valve, a float for opening said air inlet valve, and float actuated means for holding said air inlet valve open when said discharge valve is in open position.

4. An air pumping apparatus, the combination of a container having a water inlet, a water outlet in the bottom thereof, and a valve controlled air inlet and a valve controlled air outlet in the top thereof, a discharge valve for said air inlet, a float for opening said discharge valve, a latch pivoted in said container adjacent said discharge valve for holding the latter in open position, means on said latch for resisting the opening movement of said discharge valve, and a float member on said latch for actuating the same.

5. In air pumping apparatus, a container having a water inlet, a water outlet in the bottom thereof, a check valve controlled air outlet in the

top thereof, and a combined air outlet and inlet in the top thereof, a valve for controlling the combined air outlet and inlet, a float in the top of said container for opening and closing said valve, a float in the bottom of said container, and means between the latter float and the combined air outlet and inlet valve to retain said valve in open position for the admission of air through the air inlet.

6. In air pumping apparatus, a container having a water inlet and a water outlet in the bottom portion thereof, an air outlet in the top portion thereof, and a combined air outlet and inlet in the top portion thereof, a check valve in said air outlet, a valve for the combined air outlet and air inlet, a float in the upper portion of the container and connected to said last mentioned valve for opening and closing the same, a discharge valve for said water outlet, an operating rod extending from said discharge valve to the upper portion of said container, guide means for said rod, spaced stops on said rod, a float slidably mounted on said rod between the said stops, a latch mounted adjacent said discharge valve for holding the same in open position and said operating rod in raised position, a float secured to said latch for operating the same, and means on said operating rod for holding the combined air outlet and inlet valve open when said rod is in its raised position.

7. In air pumping apparatus, a container having a water inlet and a water outlet in the bottom portion thereof, an air outlet in the top portion thereof, and a combined air outlet and inlet in the top portion thereof, a check valve in said air outlet, a valve for the combined air outlet and inlet, a float in the upper portion of the container and connected to said last mentioned valve for opening and closing the same, a lever pivoted adjacent said water outlet, a discharge valve on said lever for opening and closing said water outlet, an operating rod having its lower end pivoted to said lever, guide means for the upper end of said rod, a float slidably mounted on said rod between spaced stops thereon, a float pivoted adjacent said lever, means on said float for engaging with said lever to hold said discharge valve in open position, and means on said rod for holding the valve for the combined air outlet and inlet in open position when said discharge valve is in open position.

WILLIAM U. GRIFFITHS.
